ELECTRICAL CONTROLLER FOR STEERING APPARATUS

Arthur K. Barnickel, Milwaukee, Wis., and William A. Hooks, Pascagoula, Miss., assignors, by direct and mesne assignments, to Cutler-Hammer, Inc., Milwaukee, Wis., a corporation of Delaware

Filed Aug. 4, 1958, Ser. No. 752,787
4 Claims. (Cl. 137—112)

This invention relates generally to electrical control systems. While not limited thereto, it relates particularly to a controller for shipboard steering apparatus.

For reasons of safety the hydraulic steering system on some ships is provided with two pumping units which are operable in the alternative to maintain hydraulic fluid pressure in the hydraulic system. The electrical apparatus associated with each pumping unit (i.e., the motor, solenoid valve, and contactor for the motor) is energizable from a separate source of power supply. Normally, one of the pumping units and its respective power supply is selected for operation and the other unit is maintained in readiness as an auxiliary. In certain instances, as for example, in the event of burn out of the solenoid valve coil or low voltage on the supply lines, it is desirable to transfer operation from the one unit and its respective power supply to the auxiliary.

Accordingly, it is an object of this invention to provide an improved electrical controller for automatically transferring operation from one pump unit and its source of power supply to the auxiliary.

Another object is to provide an improved controller of the aforesaid character which effects permanent transfer of operation in the event of the occurrence of one particular condition and which effects temporary transfer of operation in the event of the occurrence of another particular condition.

Still another object is to provide an improved controller of the aforesaid character wherein the one condition referred to is a solenoid valve failure and the other condition referred to is low voltage in the source of power supply.

A further object is to provide an improved controller which effects automatic and temporary transfer of operation from one electro-mechanical translating device to another in the event of a low voltage condition, and which effects retranfer to said one translating device when the low voltage condition is corrected.

Other objects and advantages of the invention will hereinafter appear.

The accompanying drawing illustrates one preferred embodiment of the invention, it being understood that the embodiment illustrated is susceptible of various modifications with respect to certain details thereof without departing from the scope of the appended claims.

Referring to the drawing, the numeral 9 designates a portion of the piping of the hydraulic steering system of a ship. Hydraulic fluid is maintained under predetermined pressure in piping 9 by operation of either the port or starboard fluid pumps 10 or 11, depending upon which is selected for operation. The pumps 10 and 11 are driven by the electric motors 12 and 13, respectively, which are energizable from independent sources of three phase A.C. electrical power supply comprising the supply lines L1, L2 and L3 and the supply lines L4, L5 and L6, respectively.

An electroresponsive contactor 14 having normally open contacts 14b, 14c and 14d in the circuit connections between lines L1, L2 and L3, respectively, and motor 12 effects energization of the latter whenever its operating coil 14a is energized. Operating coil 14a is connected on one side to line L2 and on its other side

2

to a common point X. A normally closed solenoid valve 16 is located between the discharge end of pump 10 and piping 9 and is adapted to open when its solenoid coil 16a is energized. A solenoid valve relay 18 having normally open contacts 18b and 18c in the circuit connection between lines L1 and L2, respectively, and solenoid coil 16a effects energization of solenoid coil 16a whenever its relay coil 18a is energized. Relay coil 18a is connected on one side to line L2 and is connectable on its other side to a common point Y through a normally open contact 20b of a pressure switch 20. A normally open contact 18d of relay 18 is connected in circuit between common points X and Y. The aforementioned pressure switch 20 has a pressure responsive actuator 20a in piping 9 in association with solenoid valve 16. Upon opening of solenoid valve 16 and operation of pump 10 hydraulic fluid pressure will cause actuators 20a and 21a, hereinafter described, to effect closure of contact 20b and contact 21b, respectively, and loss of pressure due to closure of valve 16 if solenoid coil 16a burns out will effect instantaneous opening of contact 20b and opening of contact 21b shortly thereafter. The operating coil 22a of a timing relay 22 is connected on one side to line L2 and on its other side to a common point Z. A normally closed contact 22b, which times open five seconds after coil 22a is energized, is connected across contact 20b. The operating coil 24a of a timing relay 24 is connected on one side to line L2 and on its other side to common point X. A normally open contact 24b of relay 24 is connected in series with a normally open contact 18e of relay 18 between common points X and Z.

A normally open contact 26a of a selector switch 26 is connected between line L1 and common point Z. Selector switch 26, which has another normally open contact 26b in circuit between line L4 and a common point W, has three positions, e.g., "Off" wherein contacts 26a and 26b are both open, "Port" wherein contact 26a is closed and contact 26b is open and "Starboard" wherein contact 26a is open and contact 26b is closed. A normally open contact 14e of contactor 14 is connected in circuit between line L1 and common point Z and is in series with a normally open contact 23c, which times closed one second after its coil is energized, of a timing relay 23, hereinafter described. A normally closed contact 23d of timing relay 23 is connected across contact 23c. A normally open contact 25c, which closes instantaneously when its coil is energized and opens two seconds after its coil deenergizes, of a timing relay 25, hereinafter described, is connected in circuit between line L1 and common point Z. A normally closed interlock contact 19f of solenoid valve relay 19 hereinafter described, is connected between common points Y and Z.

An electroresponsive contactor 15 having normally open contacts 15b, 15c and 15d in the circuit connection between lines L4, L5 and L6, respectively, and motor 13 effects energization of the latter whenever its operating coil 15a is energized. Operating coil 15a is connected on one side to line L5 and on its other side to a common point U. A normally closed solenoid valve 17 is located between the discharge end of pump 11 and piping 9 and is adapted to open when its solenoid coil 17a is energized. A solenoid valve relay 19 having normally open contacts 19b and 19c in the circuit connection between lines L4 and L5, respectively, and solenoid coil 17a effects energization of solenoid coil 17a whenever its relay coil 19a is energized. Relay coil 19a is connected on one side to line L5 and is connectable on its other side to a common point V through a normally open contact 21b of a pressure switch 21. A normally open contact 19d of relay 19 is connected in circuit between common points U and V. The aforementioned pressure switch 21 has a pressure responsive actuator 21a in piping 9 in asso-

eration with solenoid valve 17. Upon opening of solenoid valve 17 and operation of pump 11 hydraulic fluid pressure will cause actuators 21a and 20a to effect closure of contact 21b and contact 20b, respectively, and loss of pressure due to closure of valve 17 if solenoid coil 17a burns out will effect opening of contact 21b and opening of contact 20b shortly thereafter. The operating coil 23a of a timing relay 23 is connected on one side to line L5 and on its other side to common point W. A normally closed contact 23b, which times open five seconds after coil 23a is energized, is connected across contact 21b. The operating coil 25a of a timing relay 25 is connected on one side to line L5 and on its other side to common point U. A normally open contact 25b of relay 25 is connected in series with a normally open contact 19e of relay 19 between common points U and W.

Normally open contact 26b of selector switch 26, hereinbefore described, is connected between line L4 and common point W. A normally open contact 15e of contactor 15 is connected in circuit between line L4 and common point W and is in series with a normally open contact 22c, which times closed one second after its coil is energized, of timing relay 22, hereinbefore described. A normally closed contact 22d of timing relay 22 is connected across contact 22c. A normally open contact 24c, which closes instantaneously when its coil is energized and opens two seconds after its coil deenergizes, of timing relay 24c, hereinbefore described, is connected in circuit between lines L4 and common point W. A normally closed interlock contact 18f of solenoid valve relay 18, hereinbefore described, is connected between common point V and W.

The aforescribed control system operates in the following manner:

Assume that all components are in the condition shown in the drawing and heretofore described, and that the supply lines L1, L2 and L3 and the supply lines L4, L5 and L6 are energized from separate sources of supply. Further assume that it is desired to select the port pump 10 for operation and to maintain the starboard pump 11 as the auxiliary.

Selector switch 26 is moved to "Port" position to close contact 26a. Closure of contact 26a effects energization of operating coil 22a of timing relay 22 in a circuit extending from line L1, through contact 26a and coil 22a to line L2 and effects energization of coil 18a of solenoid valve relay 18 in a circuit extending from line L1, through contact 26a, through contact 19f, through contact 22b and through coil 18a to line L2. Energization of timing relay 22 effects timed closure of contact 22c with no immediate effect, opening of contact 22d with no immediate effect, and commencement of timed opening of contact 22b which will open in five seconds. Energization of solenoid valve relay 18 effects closure of contacts 18b and 18c to energize solenoid coil 16a thereby opening valve 16, closure of contact 18e with no immediate effect, opening of contact 18f with no immediate effect, and closure of contact 18d. Closure of contact 18d effects energization of coil 14a of contactor 14 in a circuit extending from line L1, through contact 26a, through contact 19f, through contact 18d and through coil 14a to line L2 and effects energization of coil 24a of timing relay 24 in a circuit extending from line L1, through contacts 26a, through contact 19f, through contact 18d and through coil 24a to line L2. Energization of contactor 14 effects closure of contacts 14b, 14c and 14d to connect port motor 12 for operation and closure of contact 14e with no immediate effect. Energization of timing relay 24 effects closure of contact 24b with no immediate effect and closure of contact 24c. Closure of contact 24c effects energization of coil 23a of timing relay 23 in a circuit extending from line L4, through contact 24c and through coil 23a to line L5. Energization of relay 23 effects timed closure of contact 23c with no immediate effect, opening of contact 23d with no im-

mediate effect, and commencement of timed opening of contact 23b with no immediate effect. Normally, upon operation of motor 12 and pump 10 with solenoid valve 16 open, hydraulic fluid pressure builds up in piping 9 and pressure switch actuator 20a responds to effect closure of contact 20b before contact 22b times open. When contact 22b times open, relay coil 18a is maintained energized through contact 20b and the motor 12 continues to operate. Build up of hydraulic fluid pressure also effects response of pressure switch actuator 21a to effect closure of contact 21b with no immediate effect.

Assume, however, that upon closure of contacts 18b and 18c solenoid valve 16 fails to open for some reason, e.g., because the coil 16a had previously burned out or was otherwise defective, or because of some mechanical difficulty. In this event, even though pump 10 starts to operate, no fluid pressure builds up in piping 9 and pressure switch contacts 20b and 21b fail to close. Then, at the end of its timing interval contact 22b opens to effect deenergization of coil 18a of relay 18. Deenergization of coil 18a of relay 18 effects reopening of contacts 18b and 18c with no effect, reopening of contact 18d, reopening of contact 18e, and reclosure of contact 18f. Reopening of contacts 18d and 18e effects deenergization of contactor 14 and deenergization of relay 24. Deenergization of contactor 14 effects disconnection of port motor 12 from its supply and effects opening of contact 14e with no immediate effect. Deenergization of relay 24 effects reopening of contact 24b with no immediate effect and timed reopening of contact 24c which remains closed for two seconds after coil 24a is deenergized. Reclosure of contact 18f effects energization of operating coil 19a of relay 19 in a circuit extending from line L4, through contact 24c, through contact 18f, through contact 23b which has not yet timed open since its timing period commenced later than that of timing contact 22b and through coil 19a to line L5. Energization of solenoid valve relay 19 effects closure of contacts 19b and 19c to energize solenoid coil 17a thus opening valve 17, closure of contact 19e with no immediate effect, opening of contact 19f with no immediate effect, and closure of contact 19d. Closure of contact 19d effects energization of coil 15a of contactor 15 in a circuit extending from line L4, through contact 24c, through contact 18f, through contact 19d and through coil 15a to line L5 and effects energization of coil 25a of timing relay 25 in a circuit extending from line L4, through contact 24c, through contact 18f, through contact 19d and through coil 25a to line L5. Energization of contactor 15 effects closure of contacts 15b, 15c and 15d to connect starboard motor 13 for operation and closure of contact 15e. Closure of contact 15e establishes a maintaining circuit for relay coils 14a, 23a and 25a and contactor coil 15a from line L4, through contact 15e and through contact 22c to common point W when contacts 24c times open. Energization of timing relay 25 effects closure of contact 25c with no immediate effect and closure of contact 25b with no immediate effect. Upon operation of motor 13 and pump 11 with solenoid valve 17 open, hydraulic fluid pressure builds up in piping 9 and pressure switch actuator 21a responds to effect closure of contact 21b before contact 23b times open. When contact 23b times open coil 19a of relay 19 is maintained energized through contact 21b and motor 13 continues to operate. Build up of hydraulic fluid pressure also effects response of pressure switch actuator 20a to effect closure of contact 20b with no immediate effect. Pump 11 will continue to operate until motor 13 is deenergized by movement of selector switch 26 to "Off".

Now assume that solenoid valve 16 closes for some reason after pump 10 has been in operation and that timer contacts 22b and 23b have previously opened. When solenoid valve 16 closes, fluid pressure in piping 9 drops off and pressure switch actuator 20a responds to open contact 20b. Pressure switch actuator 21a also re-

sponds but contact 21b opens after contact 20b. Opening of contact 20b effects deenergization of coil 18a of relay 18 with the results hereinbefore described but the circuit for the energization of coil 19a of relay 19 is initially established from line L4, through contact 24c, through contact 18f, through contact 21b and through coil 19a to line L5 rather than through contact 23b. Operation is thus transferred from pump 10 to pump 11.

Now assume that port pump 10 is in operation but that low voltage occurs in lines L1, L2 and L3. This occurrence will have the effect of deenergizing relay coils 18a, 24a and 22a and contactor coil 14a. Operation then temporarily transfers to starboard pump 11 in the manner hereinbefore described until normal voltage is restored. Coil 19a of relay 19, however, initially becomes energized in a circuit extending from line L4, through contact 24c which does not immediately open when relay 24 deenergizes, through contact 18f which closes instantaneously when relay 18 deenergizes, through contact 21b which remains closed as some fluid pressure is still maintained in piping 9 and through coil 19a to line L5. When contact 24c times open, the circuit between line L4 and common point W is maintained through contact 15e which closed when contactor 15 was energized and through contact 22d which reclosed when relay 22 deenergized. When normal voltage returns to lines L1, L2 and L3, relay 22 becomes energized in a circuit extending between line L1 through contact 26 and through coil 22a to line L2 to effect opening of contact 22d, timed closure of contact 22c and timed opening of contact 22b. Opening of contact 22d effects deenergization of relays 25, 23, 19 and contactor 15 to stop starboard motor 13. Deenergization of relay 19 effects reopening of contacts 19b and 19c, reclosure of contact 19f and relay 18 is reenergized to effect restarting of port motor 12.

If initially it is desired to select the starboard pump for operation and to maintain the port pump as the auxiliary, selector switch 26 is moved to "Starboard" position. Thereafter operation will be substantially as hereinbefore described.

It will be apparent that although the invention disclosed herein is embodied in the steering apparatus of a ship, other embodiments are possible.

We claim:

1. In combination, a pair of electrical translating devices, an independent source of electrical power supply for each of said devices, apparatus associated with each of said translating devices and adapted to operate concurrently therewith, and control means having means for selectively effecting operation of one or the other of said devices and its associated apparatus at any given time, said control means also including means to effect automatic permanent transfer of operation from a selected device to the other device upon the occurrence of a fault in the apparatus associated with said selected device, and said control means further including means to effect temporary transfer of operation from said selected device to the other upon the occurrence of a fault in the electrical power supply for said selected device until said fault in the power supply is corrected.

2. In combination, a pair of electrical translating devices each of which comprises a motor and a pump, an independent source of electrical power supply for each of said devices, a valve associated with each pump and adapted to operate concurrently therewith, and control means having means for selectively effecting operation of one or the other of said devices and its valve at any given time, said control means also including means to effect automatic permanent transfer of operation from one device to the other in the event of a failure of the

valve associated with the pump of said one device, and said control means further including means to effect temporary transfer of operation from one device to the other in the event of low voltage in the power supply for the motor of said one device until said normal voltage in the power supply is restored.

3. In combination, a pair of translating devices, independent sources of electrical power supply for each of said translating devices and a controller comprising a pair of contactors each of which is energizable to effect energization of a respective translating device from its respective source of electrical power supply and means for effecting selected energization of one or the other of said contactors, said means also including means to effect deenergization of a selected contactor and energization of the other contactor in the event of low voltage in the power supply for the translating device energized through said selected contactor, and said means further including means to effect deenergization of said other contactor and reenergization of said selected contactor upon the restoration of normal voltage in the power supply for the translating device energized through said selected contactor.

4. In combination, a pair of translating devices, independent sources of electrical power for each of said translating devices, and a controller comprising a pair of electroresponsive contactors each of which is energizable to connect respective ones of said translating devices to their respective sources of power, a pair of first electroresponsive timing relays, a pair of main electroresponsive relays, a pair of second electroresponsive timing relays and a selector switch, said selector switch being selectively operable to one position to energize one of said first timing relays and one of said main relays and to another position to alternatively energize the other of said first timing relays and the other of said main relays, energization of a selected main relay effecting energization of one of said contactors to connect a selected translating device to its source of power and energization of one of said second timing relays, said controller including means responsive to low voltage in the power supply to which the selected translating device is connected to deenergize said one of said main relays and energize the other of said main relays, energization of said other of said main relays effecting energization of the other contactor to connect the other translating device to its source of power and also effecting energization of the other of said second timing relays, energization of said other of said second timing relays establishing a maintaining circuit for said other of said main relays, and said controller further including means responsive to restoration of normal voltage in the power supply for said selected one of said translating devices to effect reenergization of said one of said first timing relays to effect deenergization of said other of said main relays and following deenergization of said other of said contactors and said other of said second timing relays, deenergization of said other of said main relays effecting reenergization of said one of said main relays to afford reenergization of said one of said contactors and said one of said second timing relays.
